United States Patent

Des. 239,395
Patented Mar. 30, 1976

239,395

PET PILLOW

Mildred M. David, 23401 Park Sorrento 10,
Calabasas, Calif. 91302

Filed Jan. 25, 1974, Ser. No. 436,498

Term of patent 14 years

Int. Cl. D30—06

U.S. CL. D30—41

FIG. 1 is a perspective view of a pet pillow showing my new design;

FIG. 2 is a bottom perspective view thereof;

FIG. 3 is a top plan view thereof;

FIG. 4 is a side elevational view thereof, all sides being substantially the same;

FIG. 5 is a perspective view of a modified form of the pet pillow; and

FIG. 6 is a bottom perspective view thereof.

I claim:

The ornamental design for a pet pillow, substantially as shown and described.
